DESIGN FOR A BOTTLE

Ronald H. Dallas, South Gate, Calif., assignor to Union Oil Company of California, Los Angeles, Calif., a corporation of California

Application August 16, 1938, Serial No. 79,372

Term of patent 7 years

To all whom it may concern:

Be it known that I, Ronald H. Dallas, a citizen of the United States residing in South Gate, county of Los Angeles, and State of California,
have invented a new, original, and ornamental Design for a Bottle, of which the following is a specification, reference being had to the drawing forming part thereof.

In the drawing Figure 1 is a front view of the bottle showing my design.

I claim:

The ornamental design for a bottle, substantially as shown.

RONALD H. DALLAS.
